Primary Examiner — Keith J Wilson(74) *Attorney, Agent, or Firm* — Jeffrey D. Moy; Weiss & Moy, PC(57) **CLAIM**

The ornamental design for a chlorinator cell, as shown and described.

DESCRIPTION

FIG. 1 is a front side perspective view of a chlorinator cell, showing my new design;

FIG. 2 is a right side view thereof;

FIG. 3 is left side view thereof;

FIG. 4 is a top view thereof;

FIG. 5 is a bottom view thereof;

FIG. 6 is a front perspective view thereof; and,

FIG. 7 is a rear perspective view thereof.

The broken lines depict portions of the chlorinator cell that are for illustrative purposes only and form no part of the claimed invention.
